[57] CLAIM

The ornamental design for a large airplane with nonplanar wing, as shown and described.

DESCRIPTION

FIG. 1 is a top plan view of a large airplane with nonplanar wing illustrating our new design;

FIG. 2 is a left side elevational view thereof in a non-flight configuration, the right side elevational view, not shown, being a mirror image of that shown;

FIG. 3 is a front elevational view of FIG. 2;

FIG. 4 is a rear elevational view of FIG. 2; and,

FIG. 5 is a bottom plan view of FIG. 2.
